UNITED STATES PATENT OFFICE.

SALVATORE PASQUALE LUCIO CALITRI, OF ROCHESTER, NEW YORK.

LUSTERLESS-GARMENT-PRESSING IRON.

1,111,438.

Specification of Letters Patent.

Patented Sept. 22, 1914.

Application filed February 3, 1914. Serial No. 816,185.

To all whom it may concern:

Be it known that I, SALVATORE PASQUALE LUCIO CALITRI, a subject of the King of Italy, residing at Rochester, in the county of Monroe and State of New York, have invented certain new and useful Improvements in Lusterless - Garment - Pressing Irons; and I do hereby declare the following to be a full, clear, and exact description 10 of the invention, such as will enable others skilled in the art to which it appertains to make and use the same.

This invention relates to new and useful improvements in pressing irons, and has for its principal object to provide an iron embodying novel and efficient means for reliably holding a pressing cloth thereon.

Still another object of the invention is to provide a simple and effective means by 20 which the pressing cloth will remain smooth over the entire surface of the iron when the device is in use.

A still further object of the invention is to provide a novel combination and arrangement of parts by means of which the above-mentioned objects may be obtained to provide a device which may be easily and quickly constructed at a minimum of expense.

With the above and other objects in view, the invention consists in the novel combination and arrangement of parts which will be fully set forth in the following specification and accompanying drawings, in which—

Figure 1 is a top plan view of an iron constructed in accordance with this invention. Fig. 2 is a longitudinal sectional view of the same, Fig. 3 is a transverse sectional view taken on line 3—3 of Fig. 2, Fig. 4 is an end view of one of the handle supporting members, Fig. 5 is a view of the coöperating handle supporting members, and Fig. 6 is a detail view of the pressing cloth holding element.

Referring now to the drawings by characters of reference, the numeral 1 designates as an entirety, the main body portion of the iron which comprises the relatively heavy bottom 2, having at its longitudinal and lateral extremities, the ends 3 and the sides 4 respectively. The ends are preferably offset as at 5 to form the decks or extensions 6 which are so arranged as to assist in sup-

porting the pressing cloth when the device is in use. A suitable top 7 is secured to the upper extremities of the extensions 5 and the top edges of the walls 4, and this portion 7 is provided with a plurality of corrugations 8. The side walls 4 are provided along their upper edges with a plurality of recesses 9, the use of which will appear as the description proceeds. A plurality of apertures 10 are formed in the walls 4 immediately beneath the plate 7 and are adapted to permit of the escape of the burnt gases when the device is in use.

Secured to the upper extremities of the walls 4, is a plate 11 which is arranged to form an air space 12, between the corrugated plate 7 and said plate 11. Secured to the plate 11 at suitable intervals are the handle supporting elements 12 and 13 which will be described in detail hereinafter. A suitable guide member 14 is secured to the plate 11, and is provided with a centrally located aperture 15, the use of which will appear as the description proceeds.

The handle supporting elements 12 and 13 which were mentioned in the foregoing paragraph, preferably comprise the body portion designated generally by the numerals 16 and 17 respectively, each of which is provided with the centrally located upstanding member 18 as illustrated in Figs. 4 and 5. The element 18 on the supporting member 12 is preferably provided with the aperture 19 extending in the longitudinal plane of the iron. A second aperture 20 is formed through the element 18 at right angles to the aperture 19. The transverse aperture 20 is preferably internally screw threaded. This member 12 is arranged to form a pivotal connection for the handle of the iron as will be more fully described. The element 18 formed on the supporting member 13 is provided with a slot 21 movably receiving the reduced end or extension 22 projecting longitudinally from the handle 23. An extension 24 projecting from the opposite end of the handle 23 is pivotally secured in the member 12 on a bolt or pivot pin 25, which latter is received within the aperture 20.

The cloth controlling element which is illustrated in Fig. 6, preferably comprises the L-shaped member 26 having pivotally

secured to its short arm the bar 27 as at 28. This bar 27 is provided at its free end with a suitable internally screw threaded aperture 29 which is adapted to coöperate with the bolt 30 extending through a suitable aperture in the long arm of the L-shaped member 26 as clearly shown. A suitable ear 31 is formed integral with the long arm intermediate its ends and is adapted to coöperate with the ears 32 formed on the connecting link 33 to form a pivotal connection 34 between the link and the L-shaped member. The upper end of the link is pivotally connected as at 35 to the free end of the extension 22 and it will be evident that when the handle extension 22 is raised, the entire frame formed by the L-shaped member and the member 27 will be raised, thus tightening the cloth on the iron.

20 The plate 11 is provided adjacent its opposite ends with upstanding lugs or supports in each of which is fitted a set screw 43 for pivotally securing arms 37 and 38 which are bent downwardly toward their free ends as at 39 and provided with rounded ends 40 which rest against the extensions 6 and are arranged to keep the pressing cloth extended to its full width. A suitable curved bar 41 is slidable through apertures 50 in each of the arms, and is so arranged as to hold the coiled spring 42 in operative relation with the arms so that said coiled spring will exert outward pressure against said arms and force the same away from each other.

40 A pair of curved plates 44 are hingedly secured as at 45 and engage the angular extensions 46. Each of these plates 44 is mounted over a suitable spring which latter is adapted to exert upward pressure against the free extremity of the plate and form what might be termed a valley where the plates are hinged. Thus it will be seen that the extension 46 will be normally held in the valley and should the same at any time come out of alignment, it will be evident that the tendency of the spring acting against the plates will be to force the extension into its normal position, thus insuring the proper relation 50 of the arms to the cloth when the device is in use.

55 In order to provide a heating means for the iron, the longitudinal pipe 47 is secured within the iron and is provided with a plurality of apertures 48 through which the gas passing through the pipe 49 passes and is ignited, thus heating the iron and insuring the proper distribution of heat over the bottom 2. The pipe 49 is connected by a flexible 60 tubing or any other suitable means indicated at 50 to a suitable source of gas supply when the device is to be used.

65 A suitable coil spring 51 is operatively connected to the free end 22 of the handle supporting member, and is adapted to exert

upward pressure thereagainst to normally hold the cloth supporting element in the raised position illustrated in Fig. 2. The cloth is arranged to pass longitudinally around the iron and through the cloth holding element and completely cover the bottom of the iron to prevent the same from coming into contact with the garment which is being pressed.

70 It will be evident that in use, the iron is placed on the article to be pressed and the cloth coming in direct contact with the surface of the iron will prevent the article being pressed from becoming shiny, thus eliminating the objectionable feature. In changing the position of the iron, it will be evident that upon exerting upward pull on the handle the frame formed by the L-shaped member 26 and the pivoted member 27 will be drawn upward between the arms of the member 14 and thus pull the cloth tight over the iron and permit the iron to be moved without any interference from the cloth.

75 While in the foregoing there has been shown and described the preferred embodiment of this invention, it is to be understood that such changes may be made in the combination and arrangement of parts as will fall within the spirit and scope of the appended claims.

80 Having thus described my invention, I claim:

1. The combination with a pressing iron of a handle pivotally secured to the iron, a pressing cloth carried by the iron, means connected to the handle to take up the fullness of the cloth when the iron is lifted, and yieldable means to hold the cloth smooth transversely of the iron.

85 2. The combination with a pressing iron of a handle pivotally secured to the iron, a pressing cloth of greater length than the iron, a frame secured to the handle, and to one end of the pressing cloth, said frame being adapted to automatically take up the fullness of the cloth when the iron is lifted, and means to hold the cloth smooth transversely of the iron.

90 3. The combination with a garment pressing iron of a handle pivotally secured to the iron, a cloth of greater length than the bottom of the iron, said cloth being adapted to permit the iron to slide freely thereover, means carried by the handle and secured to one end of the cloth to take up the fullness in the cloth, and a pair of yieldable resilient arms secured to the iron near each end and adapted to hold the cloth normally extended to its full width.

95 4. In a device of the character described, the combination with a pressing iron of a cloth of greater length than the bottom of the iron, and carried thereby, means at one end of the iron to secure one end of the cloth, a handle pivotally secured to the iron, a frame

carried by the handle, the opposite end of
the cloth being secured to the frame, resil-
ient arms secured to the iron near each end,
said arms being adapted to yieldably hold
5 the cloth fully extended laterally, and means
to hold the arms in their normal operative
position.

In testimony whereof I affix my signature
in presence of two witnesses.

SALVATORE PASQUALE LUCIO CALITRI.
